AIRCRAFT HYDRAULIC PRESSURE
SIMULATING SYSTEM

William L. Konrad, Pittsburgh, Pa., assignor to Westinghouse Air Brake Company, Wilmerding, Pa., a corporation of Pennsylvania

Application June 9, 1955, Serial No. 514,331

3 Claims. (Cl. 35—12)

This invention relates to flight simulators for pilot training, and particularly to an improved selsyn system therefor.

In flight trainers for transitional pilot training, it is important that the instrumentation of the trainer be made to correspond with that found in the particular aircraft to be simulated. Further, in the operation of the trainer, it is desirable that the indications presented by the simulated instruments correspond with the indications of actual instruments under flight conditions.

It is known to provide in such trainers a gauge simulating the pressure of the hydraulic systems supplying the servo motors which actuate the control surfaces in an actual aircraft. Basically, this pressure is controlled by a hydraulic pump which operates on a cycle which maintains the pressure between a maximum and minimum value. Previously, it has been usual to simulate the operation of the pressure indicator for such a system by simply simulating the cyclic variations in pressure caused by the periodic pumping cycle. However, in actual flight, actuation of a control surface servo motor by the pilot will cause a momentary dip in hydraulic pressure depending in magnitude and duration upon the extent of the maneuver made by the pilot and the speed of the maneuver. The present invention provides a means for simulating this dip in pressure in response to control movements made by the trainee in operating a simulator.

Accordingly, it is an object of my invention to provide an improved hydraulic pressure simulator.

It is a further object of my invention to provide an improved selsyn system for actuating the hydraulic pressure gauge in a transitional flight trainer.

It is a further object of my invention to provide an improved selsyn system for combining a plurality of signals.

It is a further object of my invention to provide an improved system for controlling a selsyn receiver in accordance with the rate of movement of a controlled object.

Other objects and further advantages of my invention will be apparent to those skilled in the art as the description proceeds.

I shall first describe an embodiment of my invention, and shall then point out the novel features thereof in claims.

The drawing comprises a single figure showing a wiring diagram of one embodiment of my invention.

Referring to the drawing, the illustrated embodiment of my invention is adapted to be employed with a flight trainer having a pilot's control stick 1 and a simulated hydraulic pressure gauge 39. Other details of the trainer may be conventional, and as they do not form a part of my present invention, they are not shown.

Hydraulic pressure indicator 39 has a needle 38 which is controlled through shaft 37 from rotor 22 of selsyn receiver 21. Selsyn 21 has a stator comprising windings 23, 32 and 33, which are connected to the stator winding

2

of a selsyn transmitter 30 through connections which will be hereinafter described. Selsyn transmitter 30 has a rotor 34 adapted to be driven through shaft 35 by a conventional hydraulic pressure simulator 36. Rotors 22 and 34 are energized from a suitable source of alternating voltage as shown.

Hydraulic pressure simulator 36 may be a conventional trainer component, adapted to provide a cyclic signal simulating the basic pumping cycle of the hydraulic system. The details of this component do not form a part of the present invention and are, therefore, not shown. However, for example, simulator 36 might comprise a motor having a conventional speed control adjusted in accordance with simulated engine speed, driving a cam to position shaft 35 cyclically between a maximum and minimum value.

Stator winding 29 of selsyn 30 is connected to stator winding 33 of selsyn 21 through lead 25 in series with resistor 27. Stator winding 28 of resolver 30 is connected to stator winding 32 through lead 24 in series with resistor 26. Stator winding 31 of resolver 30 is connected to stator winding 23 of resolver 21 through leads 19 and 20 in series with output windings 17 and 18 of a magnetic amplifier 11 for a purpose to be described. The function of resistors 26 and 27 is to balance the impedance of windings 17 and 18.

Magnetic amplifier 11 comprises a core 12 on which are wound output windings 17 and 18, in opposition, and power windings 13 and 14 connected by terminals 30 15 and 16 to a suitable source of alternating voltage. A D.C. winding 10 is also placed on the core symmetrically with respect to the other windings. As is well known in the art, when there is no bias voltage across winding 10, the voltages induced across windings 17 and 35 18 by windings 13 and 14 are 180° out of phase and there is no output voltage across leads 19 and 20. However, if a D.C. bias voltage appears across winding 10, at a particular instant one of windings 17 and 18 will be influenced by a flux at the saturation level, whereas 40 the other winding will be influenced by a flux below the saturation level. Accordingly, an output voltage will appear across leads 19 and 20 proportional to the applied D.C. voltage across winding 10.

Winding 10 is connected across a potentiometer having 45 a wiper 8 and a resistor 7 through condenser 9. Resistor 7 is connected across battery 5 through resistor 6. These components form a network 4 for producing an output voltage on wiper 8 which depends upon the position of the wiper. Wiper 8 is driven on resistor 7 by 50 mechanical connection 3 from the pilot's stick 1 which is pivoted to the framework of the simulator at 2.

The operation of this embodiment of my invention will now be described.

With stick 1 in a fixed position, and wiper 8 stationary 55 on resistor 7, no voltage will appear across winding 10 since under these conditions condenser 9 presents an infinite impedance. However, if stick 1 is moved in response to control movements by the trainee, a voltage will appear across winding 10 proportional to the rate 60 of movement of the stick. This signal will cause an output signal to appear across leads 19 and 20 proportional to the rate of movement of the pilot's stick. Since leads 19 and 20 are in the circuit connecting selsyn transmitter 30 with selsyn receiver 21, the signal on leads 65 19 and 20 will be added to the signal introduced by the movement of rotor 34 of transmitter 30. Accordingly, the rotor 22 of selsyn 21 will be positioned in accordance with the sum of the pumping cycle signal and the transient signal introduced by stick movement. Needle 70 38 of indicator 39 will accordingly indicate a temporary drop in hydraulic pressure.

Since the components of the disclosed system, and particularly the selsyn elements thereof, do not operate instantaneously, there is a finite lag between the movement of needle 38 and the initial movement of stick 1. Due to this time lag, the overall result of the introduction of condenser 9 in the system is not a perfect differentiation. Therefore, the signal appearing on the stator of resolver 21 may be considered to consist of a component of the amplitude of the movement of stick 1 as well as of the rate of movement. That is, in practice, it is found that the indication of needle 38 will be subject to a more pronounced variation when the stick is moved through a large angle than if moved through a small angle, even though at the same rate. This result is highly desirable, since in actual aircraft the pressure indicator is found to behave in substantially the same way.

While I have described an embodiment of my invention in detail, it will be obvious to those skilled in the art upon reading this disclosure that many changes and modifications in the disclosed structure could be made within the scope of my invention. Accordingly, I do not wish to be limited to the details shown, but only by the scope of the following claims.

Having thus described my invention, what I claim is:

1. A hydraulic pressure simulator for flight trainers, comprising in combination, a hydraulic pressure indicator, control means for said indicator, a magnetic amplifier connected to provide an output signal to said control means, a bias winding for determining the output signal of said amplifier, a potentiometer energized by a direct current voltage, a wiper on said potentiometer, a condenser connected in series with said bias winding and said wiper, the series circuit formed by said wiper, said condenser and said bias winding being connected across a portion of said potentiometer, a pilot's control member, and means mechanically connecting said pilot's control member to said wiper, movement of said control member causing a signal to be developed across said bias winding in accordance with the rate and extent of the movement of said pilot's control member.

2. A hydraulic pressure simulator for flight trainers, comprising in combination, a selsyn transmitter and a selsyn receiver each having a stator and a rotor, means connecting a signal indicating pressure to said transmitter rotor, means connecting said stators to each other, a hydraulic pressure indicator positioned by said receiver rotor, a magnetic amplifier, an output winding of said magnetic amplifier being connected to said stators, a bias

winding for said amplifier, a potentiometer energized by a direct current voltage, a wiper on said potentiometer, a condenser connected in series with said bias winding and said wiper, said wiper connecting said condenser and said bias winding across a portion of said potentiometer, a pilot's control member, means mechanically connecting said pilot's control member to said wiper, movement of said control member causing a transient signal across said bias winding of said magnetic amplifier in accordance with the rate and extent of the movement of said control member, whereby said receiver rotor positions said hydraulic pressure indicator in accordance with the sum of said transient signal and said signal indicating pressure.

3. In a flight trainer, in combination, a pilot's control member, a source of unidirectional voltage, a potentiometer connected across said source, a wiper on said potentiometer mechanically connected to said pilot's control member, a magnetic amplifier having a power winding, control winding and output winding, said power winding being energized by a source of alternating voltage, a condenser connected in series with said control winding and said wiper, the series circuit formed by said wiper, said condenser and said control winding being connected across a portion of said potentiometer, movement of said control member causing a transient signal to be developed across said control winding in accordance with the rate and extent of said movement, a selsyn transmitter having a stator and a rotor, a selsyn receiver also having a stator and a rotor, said rotors being energized by a source of alternating voltage, means providing a cyclic signal to said transmitter rotor, and means connecting said selsyn transmitter stator and said magnetic amplifier output winding to said selsyn receiver stator to position said receiver rotor in accordance with the sum of said cyclic signal and said transient signal.
